UNITED STATES PATENT OFFICE.

JOHN J. B. TRIX, OF DETROIT, MICHIGAN.

INJECTOR.

1,260,834.

Specification of Letters Patent. Patented Mar. 26, 1918.

Application filed December 16, 1916. Serial No. 137,296.

To all whom it may concern:

Be it known that I, JOHN J. B. TRIX, a citizen of the United States, residing at Detroit, county of Wayne, State of Michigan, have invented a certain new and useful Improvement in Injectors, and declare the following to be a full, clear, and exact description of the same, such as will enable others skilled in the art to which it pertains to make and use the same, reference being had to the accompanying drawings, which form a part of this specification.

My invention relates to injectors and an object of my improvements is to secure greater efficiency in the performance of such apparatus.

I secure this object in the device illustrated in the accompanying drawing in which,

20 The figure is a longitudinal section in elevation.

m is the discharge tube, having the spill or relief apertures *d*² through its wall. *a* is the steam chamber, *b* a suction chamber, *c* the overflow chamber and *d* is a chamber with which said relief apertures communicate.

*c*² are the overflow apertures through the wall of the tube *m* communicating with the inclosed overflow chamber *c* and *c*³ is a valve closing the otherwise open upper end of said chamber. *c*⁴ is the discharge passage with which the port of the valve *c*³ communicates. *d*³ is a valve interposed between the discharge passage *c*⁴ and the spill or relief chamber *d* and opening toward said chamber. *d*⁴ is a guide extending downward through the port in the valve *d*³ and having its lower end closely adjacent to the valve *c*³ and above the same.

The valve *d*³ reciprocates in a chamber, the cross-sectional area of which it nearly fills, so that its automatic return to its seat is retarded because the water must flow from below to above said valve.

The operation of the above described device is as follows:

In the operation of an injector, as heretofore constructed, water has been discharged from the relief or spill passages *d*² and discharged to the waste or to the overflow chamber where it re-enters the tube and is carried to the boiler or is again discharged through the passages *d*². By interposing the valve *d*³ between the chamber *d*

and the overflow passage the water discharged from the passages *d*² is held in the chamber *d* and the loss incident to its discharge or projection is obviated. When, in the action of the injector there is a discharge from the apertures *c*² a pressure accumulates in the overflow chamber *c* and this will raise the valve *c*³ which will strike against the guide *d*⁴ raising the valve *d*³ opening the chamber *d*, in which case the discharge from both the chambers *c* and *d* will pass into the discharge passage *c*⁴.

When the flow of water is established, the valve *c*³ is drawn suddenly to its seat but the flow through the passage *d*² continues until the valve *d*³ is closed when the water is projected directly into the boiler.

What I claim is:

1. In an injector having an overflow chamber, a discharge tube having a relief passage through the wall thereof, a closed chamber into which said passage opens, a port in the wall of said closed chamber, a valve controlling said port, closing with the pressure in said chamber and opening against said pressure, and automatic means actuated by the pressure in the overflow chamber for opening said valve.

2. In an injector having an overflow chamber, a discharge tube having a relief passage through the wall thereof, a closed chamber into which said passage opens, a port in the wall of said closed chamber, a valve controlling said port, closing with the pressure in said chamber and opening against said pressure, and means for retarding the closing motion of said valve.

3. In an injector having an overflow chamber, a discharge tube having a relief passage through the wall thereof at the narrowest portion of the bore of said tube, a closed chamber into which said passage opens, a port in the wall of said closed chamber, a valve controlling said port, closing with the pressure in said chamber and opening against said pressure, and automatic means actuated by the pressure in the overflow chamber for opening said valve.

4. In an injector, an overflow chamber *c*, a discharge tube *m* opening at one end into said overflow chamber, a port *d*² through the wall of the discharge tube at a distance from its end which opens into said overflow chamber, a closed chamber *d* separated from the boiler and from the overflow chamber

into which the passage d^2 opens, a valve d^3 opening toward the chamber d and adapted to close the port through the wall of said chamber, a valve c^3 adapted to be opened by pressure in the overflow chamber and to close toward said chamber, said valve being adapted to force the valve d^3 open as the

valve c^3 rises from its seat, said valves being arranged so that the valve c^3 shall close before the valve d^3 , substantially as and for the purpose described.

In testimony whereof, I sign this specification.

JOHN J. B. TRIX.
